UNITED STATES PATENT OFFICE

JAMES G. BLUNT, OF SCHENECTADY, NEW YORK

HUB LINER FOR RAILROAD VEHICLES

Application filed February 9, 1928. Serial No. 252,987.

This invention relates to appliances of the general class or type known as hub liners, which are interposed between the journal boxes of railroad vehicles and the wheel hubs adjoining them, for the purpose of absorbing lateral pressure in passing around curves. The type referred to is instanced in Letters Patent of the United States No. 1,551,005, granted and issued to James G. Blunt, under date of August 25, 1925, upon which the present invention is an improvement.

The object of the invention is to provide a hub liner having the operative advantages of that set forth in Patent No. 1,551,005 aforesaid, and in addition, the structural advantage of capability of application in connection with journal boxes of such form as would preclude the applicability of the hub liner of said patent.

20 The improvement claimed is hereinafter fully set forth.

In the accompanying drawing: Figure 1 is a vertical axial section, through a journal box and wheel hub, illustrating an application 25 of the invention in connection therewith; Fig. 2, a side view, in elevation, of the hub liner; and, Fig. 3, a view, in perspective, on an enlarged scale.

In the practice of the invention, referring 30 descriptively to the specific embodiment thereof which is herein exemplified, a wear plate, or liner, is interposed between the outer end of a journal box, 1, and the hub of the adjacent wheel, 4, said liner being of sectional construction, and comprising two counter- 35 part members, or sections, 2, 2. The two sections abut, one against the other, in the vertical axial plane of the liner, and are detachably connected by a bolt, 3, passing through bolting lugs, 2^a, one at the bottom of each of the sections. The bolt, 3, is drawn to a tight bearing by a nut, 3^a.

In applying the hub liner, the sections may 45 be separately slipped upward to position, relative to the axle, 4^a, without dropping the wheels, and when in position, are supported on the journal box by inwardly and downwardly inclined dove-tailed tongues, 2^b, 50 one on each of the sections, and thereafter

bolted together at their bottoms, by the connecting bolt, 3.

An open top oil recess, or recesses, may be formed in each of the sections, from which oil is supplied to the face of the hub liner, through passages, 2^c. The oil recess, oiling grooves, and tongues are substantially similar to the corresponding members of the hub liner of Patent No. 1,551,005 aforesaid, and do not form part of the present invention.

It will be obvious to those familiar with the construction of railroad rolling stock, that the invention herein set forth is of substantial practical value in the capability which it affords of application in connection with journal boxes of types now in service; in which the space above the hub liner is so limited by other members as to render it impossible to locate a connecting bolt in such space. Further, the capability of inserting 70 the hub liner from below, without dropping the wheels, is a valuable feature.

The invention claimed as new and desired to be secured by Letters Patent is:

1. A hub liner composed of two counter- 75 part sections, each section having a face at the top portion adapted to be opposite a face of the other section when the sections are assembled, and an inner face having side and upper portions adapted to cooperate with an 80 inner face of the other section having side and upper portions, when the parts are assembled, to surround the sides and top of a portion of the journal; a tongue projecting from each of the sections adapted to fit in a groove in the journal box, the tongues being 85 directed for assembling the sections by movements thereof toward the vertical axial plane of the journal; and means for engaging the sections at the bottom thereof for securing 90 the sections together.

2. A hub liner composed of two counter- 95 part sections, each section having a face at the top portion adapted to be opposite a face of the other section when the sections are assembled, and an inner face having side and upper portions adapted to cooperate with an inner face of the other section having side and upper portions, when the parts are assembled 100 to surround the sides and top of a por-

- tion of the journal; an inclined tongue projecting from each of the sections directed upwardly toward said top face and adapted to fit in a groove in the journal box, the tongues being directed for assembling the sections by movements thereof upwardly and towards the vertical axial plane of the journal; and means for engaging the sections at the bottom thereof for securing the sections together.
- 10 3. A hub liner composed of two counterpart sections, each section having a face at the top portion adapted to be opposite a face of the other section when the sections are assembled, and an inner face having side and upper portions adapted to cooperate with an inner face of the other section having side and upper portions, when the parts are assembled to surround the sides and top of a portion of the journal; an inclined tongue having a bevelled face projecting from each of the sections, directed upwardly toward said top face adapted to fit in a similarly bevelled groove in the journal box, the tongues being directed for assembling the sections by movements thereof upwardly and towards the vertical axial plane of the journal; and means for engaging the sections at the bottom thereof for securing the sections together.
- 15 4. A hub liner composed of two counterpart sections, each section having a face at the top portion adapted to be opposite a face of the other section when the sections are assembled, and an inner face having side and upper portions adapted to cooperate with an inner face of the other section having side and upper portions, when the parts are assembled to surround the sides and top of a portion of the journal; an inclined tongue having a bevelled face projecting from each of the sections, directed upwardly toward said top face, adapted to fit in a similarly bevelled groove in the journal box, the tongues being directed for assembling the sections by movements thereof upwardly and towards the vertical axial plane of the journal; a flange projecting along the bottom edge of the liner having an outwardly and upwardly bevelled upper face adapted to engage a correspondingly bevelled face along the bottom of the journal box, for cooperating with the engaging bevelled faces of the tongues to secure the liner against displacement in an axial direction; and means for securing the sections together.

JAMES G. BLUNT.
